ELECTRIC SWITCH

Royal G. Nelson, Freeport, Ill., assignor, by mesne assignments, to First Industrial Corporation, Wilmington, Del., a corporation of Delaware

Application January 28, 1944, Serial No. 519,983

6 Claims. (Cl. 200—67)

1

This invention relates to electric switches and more particularly to a switch having a novel contact mechanism particularly adapted for snap switches of the type having a cantilever mounted over-center snap spring system for operating the switch.

A primary object of the invention is to provide a snap switch of the above character with a greater circuit capacity and an improved contact construction wherein the mobile contacts are self-adjusting and aligning so that good engagement is secured with the stationary contacts in spite of misalignment in the contact driving means.

Another object of the invention is the provision of a switch of the type having an overcenter snap spring system for moving the mobile contacts, and a plurality of stationary contacts engaged thereby, wherein a novel support for the mobile contacts is provided which functions to correct for angularity of the spring system and misalignment of the stationary contacts, and thereby produce substantially uniform contact pressure of the mobile contacts against the stationary contacts.

Other objects and advantages will appear from the following description and the accompanying drawings, in which—

Figure 1 is a vertical section taken longitudinally through a switch embodying the invention;

Fig. 2 is a section similar to Figure 1 showing the plunger depressed and the contacts in the opposite position;

Fig. 3 is a top view of the switch mechanism with the cover thereof removed;

Fig. 4 is a section on the line 4—4 of Figure 1;

Fig. 5 is a section on the line 5—5 of Fig. 2, and

Fig. 6 is a fragmentary view showing the mounting for the H member.

The present invention is concerned primarily with small precision type snap acting switch mechanism of the type adapted to be operated by very small pressure and movement, and adapted to switch relatively heavy electrical loads. The embodiment of the invention herein shown comprises a base 14 of insulating material which is so shaped as to form part of a housing for the switch mechanism. Disposed on the top of the base to complete the housing structure is a cover 15. Attached to the upper face of the cover 15 are upstanding pairs of tabs 16 and 17 for the attachment of wires to connect the switch into suitable circuits. In this instance, the tabs 16 and 17 are recessed into the surface of the cover and secured therein by rivets, as indicated at 18, which rivets pass through the top wall of the cover and also act to secure thereto within the housing spaced pairs of contacts 19, 19a, 21 and 21a. Likewise, the bottom of the base 14 has spaced pairs of tabs 22 and 23 secured to the base in the same manner as the tabs 16 and 17, as by rivets 24, which rivets

2

likewise retain against the interior of the base spaced pairs of contacts 25, 25a, 26 and 26a. The base 14 has an upstanding portion 27 providing a horizontally disposed shoulder 28 against which is attached one end of a leaf spring 29. The spring is rigidly and fixedly attached thereto in cantilever fashion by means of a plate 31 and screw 32, the plate projecting forwardly into the cavity of the housing and being formed upwardly, as shown at 33, in spaced relation to the switch spring. The forward end of the plate converges, as shown at 34, and has an opening 35 for the passage therethrough of an actuating pin 36 carried in the cover 15 and adapted to engage the spring system, presently to be described, for the purpose of actuating the switch mechanism.

In this instance, the spring system is made substantially in accordance with the principle disclosed and claimed in a copending application of Edward Meyer, Serial No. 519,984, filed January 28, 1944, now Patent No. 2,425,159, issued August 5, 1947. The switch spring 29 comprises a somewhat rectangular shaped piece of relatively thin spring material, such as beryllium copper, having a part of the central portion removed, as by stamping, to provide side members 37 and 38 and end members 39 and 41, the end 41 being secured under the plate 31. Projecting from the end member 41 is an actuator element 42 which projects outwardly therefrom into the central space 43 and is of decreasing width terminating in a point, as shown at 44. Also disposed in the central area of the switch spring is a U-shaped portion having legs 45 and 46 connected by an end portion 47, the opposite ends of the legs being connected, as shown at 48 and 49, to the side members 37 and 38 intermediate the ends of the side members.

Cooperating with the switch spring to provide an over-center spring mechanism is an H-shaped driving element, such as shown in Fig. 5, having an upper bar 51, lower bar 52, and a connecting portion 53, the connecting portion being adapted to seat against a point 50 (Fig. 6) on the inner edge of the free end 47 and the bars being of sufficient length to overlie the side members 37 and 38, as shown in Fig. 5. On one side of the driving element is a spring pad 54 adapted for the support of one end of an expansion member comprising a coiled expansion spring 55, the opposite end of the coiled spring having a pad 56 provided with a depression for the reception of the pointed end 44 of the actuating element 42. The expansion member forms a resilient connection between the free end 47 of the switch spring and the free end 44 of the actuator element 42.

It will be seen that the switch spring and the expansion spring 55 together form two interdependent systems, one of these systems comprising a coil spring 55, the end 47, the legs 45

and 46, the H-shaped driving element, the switch spring portions 57 and 58, and the actuator element 42 constituting an overcenter snap spring driving system, and the spring portions 59 and 61 and end 39 forming a resilient driven system. Because of the flexibility of the switch spring, the driven system is movable with the driving system and also is movable with lost motion with respect to the driving system.

In the specific embodiment of the switch shown, the position of the parts shown in Figure 1 is the normal position of the switch mechanism, the mobile contacts being disposed in engagement with the lower stationary contacts. When the plunger 36 is depressed, the actuator element 42 is moved from the position of Figure 1 to the position of Fig. 2, during which movement the point 44 of the actuator element is initially moved downward toward the compression center line of the switch spring against the compression of the expansion member 55. When this point is moved through the axis of maximum stress the spring system reverses its position to that shown in Fig. 2 with a snap movement, carrying the resilient driven system with it. The modulus of the actuator element 42 is such that when the plunger is moved downwardly until the downward force exerted by the end thereof slightly exceeds the upward component of the force exerted through the expansion member by 30 legs 45 and 46, downward motion at an accelerated rate occurs due to the fact that the slope of the force-movement curve of the expansion element is greater than that of the actuator element. During the initial part of the snap movement the bar 51 moves away from the side members 59 and 61 and the bar 52 approaches the lower side of the side members, the initial part of the snap movement thus being utilized in lost motion as between the spring system and the driven system to permit the spring system to gain velocity before the bar 52 strikes the driven system so as to impart thereto a hammer blow to break loose any minor welding of the contacts which may have occurred and to drive the mobile contacts rapidly to the opposite position.

Attached to the end member 39, as by pin in the form of a rivet 62, is a contact support comprising a strip of insulating material 63 which projects outwardly from the end member 39, as best shown in Fig. 3 in somewhat exaggerated form for the purpose of illustrating the operation, the insulating strip being conveniently formed to provide legs 64 and 65 for the purpose of supporting a pair of contacts 66 and 67. Substantial clearance is provided between the unit and the opening in the strip of insulation and between the head of the rivet and the contact support to permit the entire contact support to move within limits with respect to the end member 39 and to engage both pairs of upper or lower contacts 19, 19a, and 21, 21a, (or 25, 25a and 26, 26a depending upon the position of the switch) and to tilt with respect to the end member so as to bring it into a position approaching parallelism with respect to the plane of the contacts in spite of the angular position of the spring. Stops in the form of shoulders 60 on the switch spring prevent excessive rotation of the contact holder about the rivet 62. Each of these contacts comprises pin in the form of a rivet 68 having heads on opposite ends thereof, the rivet passing through a U-shaped connecting member or strap 69 which passes around the 75 said free end and said carrier shaped for move-

edge of the insulating material, the rivet passing through the upper and lower legs thereof. The openings in the arms 64 and 65 are of such size that the shank of the rivets 68 can slide freely therethrough and are capable of limited tilting movement. The arms are so positioned that in the opposed positions of the switch the heads of the rivets engage either the contacts 19, 19a and 21, 21a, as shown in Fig. 2, or the contacts 25 and 26, as shown in Figure 1, the rivet heads spanning the space between the spaced contacts to provide a conducting path therebetween. The loose mounting of the rivets permits the contacts to be individually self-aligning between the contacts 19 and 21 or the contacts 25 and 26 through tilting movement of the contacts about an axis transverse to the switch.

It will be seen that in order to establish good and satisfactory engagement at the stationary contacts it is essential that the mobile contacts engage each of the four upper or lower contacts with a substantial contact pressure so as to prevent arcing and spitting at the contacts. The difficulty as a practical matter of uniformly arranging these contacts in accurate coplanar relationship at the correct angles and uniform dimensions will be appreciated. The necessity for this uniformity is avoided by making the mobile contacts in the manner described so that they can tilt on a lateral axis to accommodate for such irregularities in manufacture. Likewise, this arrangement accommodates for any difference in angularity between the plane of the contact support and the plane of the engaging faces 35 of the stationary contacts.

On the other hand, the mounting of the contact support loosely on the rivet 62 with only sufficient clearance to permit of the necessary realignment causes each of the spaced mobile contacts 68 to be brought into engagement with their respective pairs of contacts 19, 19a and 21, 21a (or 25, 25a and 26, 26a) in spite of any variation in the planes of these contacts and in spite of the angularity of the spring with respect to the plane of the stationary contacts.

While the construction shown in the drawings is such that the spring and contacts are self-returning, these can be made for manual reset by regulating the unstressed shape of the actuator element 42 and by adjusting the positions of the contacts or stops in accordance with the teachings of the art.

I claim:

1. The combination in a precision switch of a switch spring having a free end movable in an arc between opposed positions, a contact carrier of insulating material mounted on said free end, a plurality of spaced mobile bridging contacts on said carrier, a plurality of spaced pairs of spaced fixed contacts, each pair being positioned for engagement by one of said mobile contacts to limit the movement of said free end in one direction and thereby define one of said opposed positions, means for mounting each of said mobile contacts on said carrier comprising a U-shaped strap having ends spaced a substantially greater distance than the thickness of said carrier and an intermediate portion extending around the edge of said carrier and a connecting member passing loosely through said carrier to permit tilting of said contact and strap with respect to said carrier under the force of said switch spring, and means for mounting said carrier on said free end comprising a pin passing through 75 said free end and said carrier shaped for move-

ment of said carrier circumferentially of the pin and about an axis transverse with respect to said pin, and means for limiting the circumferential and transverse movement of said carrier.

2. The combination in a precision type switch, of a switch member mounted at one end, means for effecting movement of the opposite end thereof with snap motion between two opposed positions, a plurality of spaced fixed contacts arranged in spaced pairs adjacent said opposite end, a contact carrier of insulating material mounted on said opposite end, a plurality of movable bridging members on said carrier positioned to engage the fixed contacts to limit the movement of said opposite end in at least one of said positions and to apply contact pressure thereto, said bridging members each being positioned to bridge between the contacts of one of said pairs of stationary contacts, said bridging members each being mounted for independent universal movement on the carrier to align each of the bridging members with the corresponding pair of fixed contacts engaged thereby in response to engagement of the bridging member therewith for the application of uniform contact pressure between the bridging member and the fixed contacts, and means for mounting said carrier on said opposite end for limited universal movement with respect thereto in response to engagement of the bridging members with the fixed contacts to align the carrier with respect to the pairs of fixed contacts and thereby accommodate for variations in the relative positions of said pairs of stationary contacts and for variations in the angularity of said opposite end of the switch member.

3. The combination in a precision switch of a switch member having a free end movable between opposed positions, a contact carrier of insulating material mounted on said free end, a plurality of spaced mobile bridging members on said carrier, a plurality of spaced pairs of spaced fixed contacts, each pair being positioned for engagement by one of said bridging members to limit the movement of said free end in one direction and thereby define one of said opposed positions, means including a pin extending through a larger sized opening for mounting the bridging members on the carrier for limited universal movement with respect to the carrier for independent self alignment of said bridging members with each pair of fixed contacts in response to engagement thereof with the pairs of fixed contacts, and means including a pin extending through a larger sized opening for mounting said carrier for limited universal movement with respect to said free end in response to engagement of the bridging members with the respective pairs of fixed contacts for self alignment of the carrier whereby to effect a relatively uniform contact pressure between the bridging members and the engaged pairs of fixed contacts.

4. The combination in a precision switch of a switch member having a free end movable between opposed positions, and spring means for urging said free end into the opposed positions, a contact carrier of insulating material mounted on said free end, a plurality of spaced mobile bridging members on said carrier, a plurality of pairs of spaced fixed contacts adjacent one side of said free end, a plurality of pairs of spaced fixed contacts adjacent the opposite side of said free end,

said pairs being arranged in opposition for alternate engagement by said bridging members in the opposed positions of said free end to complete alternate circuits therethrough and to limit the movement of said free end in opposite directions, thereby defining said positions, means for mounting said bridging members on said carrier for limited universal movement with respect to the carrier in response to engagement of the bridging members with the respective stationary contacts, and means for mounting said carrier for limited universal movement with respect to said free end for alignment thereof whereby to bring the bridging members into engagement with the pairs of fixed contacts under the force applied by said spring means.

5. In a precision snap switch the combination of, an elongated switch member mounted at one end and having the opposite end shiftable between opposed positions, a plurality of pairs of spaced, fixed contacts on each side of said switch member arranged so that the pairs of contacts are spaced laterally of the switch member and the contacts of each pair are in spaced relationship, a mobile contact carrier, means for mounting said carrier on said switch member for limited universal movement of the carrier with respect to the switch member, contacts arranged to bridge each respective pair of spaced contacts on either side of said switch member, means including a pin passing through said carrier for mounting said bridging contacts on said carrier for limited universal movement of each bridging contact with respect to the carrier, said mounting means for the carrier and the bridging contacts effecting self-alignment of each bridging contact with the respective pair of contacts as the switch member is shifted from one position to the other.

6. In a precision snap switch the combination of, an elongated switch member mounted in a cantilever fashion at one end and having the opposite end shiftable between opposed positions, a plurality of pairs of spaced, fixed contacts on each side of said switch member arranged so that the contacts of each pair are in spaced relationship, a mobile contact carrier, means for mounting said carrier on said switch member for limited universal movement of the carrier with respect to the switch member, stops for limiting the rotational motion of the carrier around the mounting axis, a contact arranged to bridge each pair of spaced contacts, means for mounting said bridging contacts on said carrier for limited universal movement of each bridging contact with respect to the carrier, said mounting means for the carrier and the bridging contacts effecting self-alignment and a good wiping contact of each bridging contact with each respective pair of contacts as the switch member is shifted from one position to the other.
